CLAIM

The ornamental design for a reconfigurable toy power shovel, substantially as shown and described.

DESCRIPTION

FIG. 1 is a side perspective view of a reconfigurable toy power shovel showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is another side perspective view of the design shown in FIGS. 1 through 6 in a humanoid robot reconfiguration;

FIG. 9 is a front elevational view thereof;

FIG. 10 is a rear elevational view thereof;

FIG. 11 is a top plan view thereof;

FIG. 12 is a bottom plan view thereof;

FIG. 13 is a right side elevational view thereof; and,

FIG. 14 is a left side elevational view thereof.
